TOY WHISTLE

John H. Jones, Alhambra, Calif.

Application May 12, 1948, Serial No. 146,310

Term of patent 14 years

(Cl. D34—15)

To all whom it may concern:

Be it known that I, John H. Jones, a citizen of the United States, residing at Alhambra, in the county of Los Angeles and State of California, have invented a new, original, and ornamental Design for a Toy Whistle, of which the following is a specification, reference being had to the accompanying drawing, forming a part thereof.

I claim:

The ornamental design for a toy whistle, substantially as shown.

JOHN H. JONES.
